(No Model.)

P. MOTLEY.
SAFETY GATE.

No. 605,502.

Patented June 14, 1898.

UNITED STATES PATENT OFFICE.

PETER MOTLEY, OF PHILADELPHIA, PENNSYLVANIA.

SAFETY-GATE.

SPECIFICATION forming part of Letters Patent No. 605,502, dated June 14, 1898.

Application filed October 8, 1897. Serial No. 654,581. (No model.)

To all whom it may concern:

Be it known that I, PETER MOTLEY, a citizen of the United States, residing at Philadelphia, in the county of Philadelphia and State of Pennsylvania, have invented a certain new and useful Improvement in Safety-Gates, of which the following is a specification.

My invention relates to a new and useful improvement in extension safety-gates, and 10 has for its object to provide such a device which may be adapted to various-sized openings, such as window-casings or doorways, and render said openings safe against accident to children playing in proximity thereto.

15 With these ends in view this invention consists in the details of construction and combination of elements hereinafter set forth, and then specifically designated by the claims.

In order that those skilled in the art to 20 which this invention appertains may understand how to make and use the same, its construction and operation will now be described in detail, referring to the accompanying drawings, forming a part of this specification, in 25 which—

Figure 1 is a perspective of a gate made in accordance with my improvement; and Fig. 2, an elevation of the same, a portion thereof being in section, so as to illustrate the operating parts thereof.

In carrying out my invention as here embodied I construct the main section of the gate from suitable rails A and uprights B and B' and partly close the space between said 35 rails by the slats C, or this portion of the gate may be made in any other suitable manner, the design thereof being immaterial. As here shown, one end of the gate is provided with recesses or guideways D, formed in the top 40 and bottom rails, and within these guideways are fitted the sliding bars E in such manner that they may be drawn outward or slid inward, as desired, and this movement of the slide-bars is limited by means of a screw F, 45 having a washer G thereunder, and also by the yoke H, through which passes a bolt I, also passing through the inner end of the lower slide-bar. The outer ends of the slide-bars are connected by the uprights B², and this 50 portion of the gate may be automatically distended by the spring J, which is coiled at K,

and held in place within a suitable socket formed in the post B by a pin L.

A gate of this construction may be swung by suitable hinges secured to the upright B' 55 in a doorway, so that the door itself may be left open, while at the same time small children will be prevented from passing through the doorway, or when occasion requires the gate may be fitted in the guideways of a window-easing after the window has been partly raised, after the manner of a fly-screen, thus affording ventilation, while at the same time avoiding the possibility of accident to children playing in proximity to said window. 65

The adjustability of the upright B² adapts this gate for use in connection with openings of varying width within certain limits, and, if desired, the sliding bars E may be locked in any adjustment by means of the sliding 70 bolts M, which are held in place in any suitable manner, their inner ends being threaded and running into a turnbuckle N, so that by the proper manipulation of this turnbuckle the pointed ends of the slide-bolts may be 75 forced into the slide-bars, as clearly shown in Fig. 2, thus locking the sliding member of the gate in the desired adjustment. This arrangement is especially desirable when the gate is to be hinged, and is intended for constant use 80 in the passing to and fro of older persons, since this to-and-fro movement of the gate would be interfered with were the sliding member left free to vary its adjustment when this end of the gate was swung out of the 85 casing.

When my improvement is intended for use only in connection with a window-easing or the like, a sliding member similar to that just described may be connected with the opposite end of the gate, thereby increasing its capacity for adjustment twofold, as will be 90 readily understood.

Other slight modifications might be made in the construction here shown and described without departing from the spirit of my invention, and I therefore do not wish to be limited to these exact details.

Having thus fully described my invention, what I claim as new and useful is—

1. In combination with the body of a gate of the character described, a sliding member

consisting of the sliding bars fitting within the body of the gate, an upright connecting said bars, and bolts arranged on the body of the gate to engage said bars and hold the sliding member in adjustment, substantially as set forth.

2. In combination with the body of the gate of the character described, a sliding member consisting of the upright, bars projecting therefrom and telescopically arranged in the body of the gate, stops carried by the bars adapted to abut an upright of the body to limit the movement of the sliding member, bolts arranged on said body, a turnbuckle threaded on the inner ends of the bolts forcing the outer ends into engagement with the sliding bars, and a spring between the body

of the gate and the upright of the sliding member, as and for the purpose set forth.

3. In combination with the body of a gate of the character described, a sliding member consisting of the bars E and an upright B², a spring arranged to force said member outward, sliding bars M attached to the body having pointed ends, and a turnbuckle for forcing said ends into the bars E, substantially as and for the purpose set forth.

In testimony whereof I have hereunto affixed my signature in the presence of two subscribing witnesses.

PETER MOTLEY.
